UNITED STATES PATENT OFFICE.

GEORGE N. HEIN, OF SAN FRANCISCO, FRANK L. PLATT, OF BERKELEY, AND ROBERT R. IMPEY, OF SAN FRANCISCO, CALIFORNIA.

DISPENSING FAUCET.

Application filed June 19, 1926. Serial No. 117,012.

The present invention relates to improvements in valves, and more particularly to that type of fluid valve commonly termed a faucet.

5 The invention has for its objects to provide a valve structure wherein the valve preferably formed with a transverse face engages the conical face of the seat with a wiping action thereby ensuring a tight contact between the valve and seat when desired; to provide a structure wherein the valve and seat are of metal preferably of different hardness; to provide a valve structure wherein is provided a second valve for precluding the flow of fluid through the valve body at such time as the main valve stem may be removed for repair or renewal; to provide a structure wherein the cut-off valve is automatically operated to seat and 10 unseat on the movement of the main stem a predetermined distance in either direction.

With the above mentioned and other objects in view, the invention consists in the novel construction and combination of parts 25 hereinafter described, illustrated in the accompanying drawings, and set forth in the claims hereto appended, it being understood that various changes in the form, proportion, size and minor details of construction within 30 the scope of the claims may be resorted to without departing from the spirit or sacrificing any of the advantages of the invention.

In the drawings wherein like characters 35 of reference designate corresponding parts Fig. 1 is a view in side elevation of one embodiment of our invention.

Fig. 2 is a view in longitudinal section.

Fig. 3 is a view in enlarged detail.

40 Fig. 4 is a sectional view on line 4-4 of Fig. 3.

Referring to the drawings wherein like characters of reference designate corresponding parts, 1 indicates a faucet or valve body provided with a fluid inlet channel 2, an outlet channel 3, a transverse dividing wall 4 provided with a channel 5 connecting channels 2 and 3. The channel 5 is shouldered at 6, and within the same is 45 movably positioned a tubular metallic valve seat 7, its lower face being inwardly beveled at 8, and its upper face being similarly beveled at 9. The valve body in alignment with the connecting channel 5 is provided in its outer wall with the respective threaded open-

ings 10 and 11, the opening 10 being closed by a plug 12 threaded thereinto and provided with a recess 13 in alignment with the channel in the tubular seat 7. Threaded into the threaded opening 11 is a valve stem 14 its upper end carrying a laterally extending operating handle 15. Centrally of its end, the stem 14 is formed with a polygonal recess 16 channeled at 17, the recess being adapted to receive the polygonal extension 18 of the metallic valve 19, the lower end of which is cylindrical and transversely faced at 20 to seat on the beveled face 9 of the seat 7. The extension 18 is formed with pairs of parallel sidewalls and is peripherally 25 grooved at a point opposite the groove 17, and when the parts are assembled as in the drawing, it is adapted to receive a portion of split spring ring 21, the ring affording a detachable connection between the valve 20 and its stem.

Reciprocally mounted within the recess 13 in the plug 12 is a conical valve 22, the skirt 23 of which is guided by the walls of the recess 13, and said valve is normally forced 28 from said recess toward the conical face 8 of the seat 7 by the coiled spring 24. A part 25 extends from the valve 22 through the tubular seat 7 into a recess 26 in the under side of the valve 19.

The threaded opening 11 is circumferentially channeled at 27 near its upper end, and from said channel extends a by-pass 28 connecting with the outlet channel 3 at a point removed from the connecting channel 5. The valve stem 14 near its upper end is circumferentially grooved at 29 to register with the groove 27 and affords a means for by-passing any leakage of fluid which may arise around the valve stem 14 and discharge 33 it through the outlet channel 3. The by-pass 28 and channels 27 and 29 are of sufficient area to take care of any seepage fluid passing between the threaded surface of the stem 14 and the threaded opening 11.

The valve 19 and seat 7 are both of metal, but the same differ in hardness enabling one to go slightly into the other during the wiping contact between the two and enable the formation of a tight seat at all times when 40 the valve is in contact with the beveled surface 9.

When it is desired to remove the valve 19 for any reason, the operator merely rotates the stem 14 to raise the stem within the 45

threaded opening 11, which operation enables the spring 24 to correspondingly elevate the valve 22 with the upward movement of the stem until such time as the valve 22 contacts with the beveled face 8 of the tubular seat 7, at which time the flow of fluid from the channels 2 and 3 will be precluded. After repairs or replacements have been made in the valve 19 or its associated parts, the stem 14 is threaded into the opening 11 to cause the part 25 to engage with the upper end of the recess 26 in valve 19, and at such time as the stem 14 is moved the required distance toward the transverse wall 4, the valve 22 will be gradually moved away from its seat, and then a rapid rotation of the stem 14 will cause the valve 19 to engage its seat and preclude further flow of fluid from the valve structure.

20 We claim:—

1. A dispensing faucet comprising a body provided with a discharge channel extending therethrough, a tubular valve seat within said channel provided with a conical face at one end, a valve stem mounted within said body for movement to and from said valve seat, a valve carried by the stem and provided with a cylindrical end having a transverse face for reception within said tubular seat with a wiping contact with said conical face on the operation of said valve stem, and means for detachably securing the valve to said stem.
2. A dispensing faucet comprising a body provided with a discharge channel extending therethrough, a tubular metallic valve seat within said channel provided with an inverted conical face at one end, a metallic valve provided with a cylindrical end having a transverse face for reception within said tubular seat, means extending exteriorly of the body for operating said valve with a wiping action against said conical face, said valve and seat differing in hardness.
3. A dispensing faucet comprising a body provided with a discharge channel extending therethrough, a tubular valve seat within said channel provided with a conical face at one end, a valve stem mounted within said body for movement to and from said valve seat, a valve carried by the stem and provided with a cylindrical end having a transverse face for reception within said tubular seat with a wiping contact on said conical face on the operation of said valve stem, said stem provided with a polygonal recess, said valve provided with a polygonal

extension for reception within said recess, and means within said recess for engaging the extension for detachably uniting the 60 parts.

4. A dispensing faucet comprising a body provided with a discharge channel extending therethrough, a tubular valve seat of relatively soft metal within said channel and provided with a conical face, a valve stem mounted within said body for movement to and from said valve seat, a valve of a softer metal than said seat carried by the stem and provided with a cylindrical end the peripheral edge of which is adapted to coact with said conical face with a wiping action on the operation of said valve stem, and means for detachably securing the valve to said stem.

5. A dispensing faucet comprising a body provided with a discharge channel extending therethrough, a tubular valve seat within said channel provided with a conical face, a valve stem mounted within said body for movement to and from said valve seat, and a metal valve carried by the stem and formed with a cylindrical end having a transverse face providing a relatively sharp peripheral edge for contacting with said conical face 85 with a wiping action.

6. A dispensing faucet comprising a body provided with a discharge channel extending therethrough, a tubular valve seat within said channel provided with a conical face at 90 one end, a valve stem threadably mounted within said body for movement to and from said valve seat, a valve carried by the stem having substantially parallel side walls and formed with a cylindrical end having a 95 metallic transverse face providing a relatively sharp peripheral edge for contacting with said conical face with a wiping action.

7. A dispensing faucet comprising a body provided with a discharge channel and formed at one end of said channel with a conical valve seat face, a valve stem mounted within the body for movement to and from the seat face, a valve carried by the stem and provided with a cylindrical end having a 100 transverse face for reception on the operation of the valve stem within the discharge channel with a wiping contact with said conical seat face.

In testimony whereof we have signed our names to this specification.
